(57) **CLAIM**

The ornamental design for the plant thirst indicator, as shown and described.

DESCRIPTION

FIG. 1 is a perspective view of the plant thirst indicator incorporating my new design and indicating a fully watered plant;

FIG. 2 is a front view thereof;

FIG. 3 is a side view thereof, the opposite side being symmetrical to the side shown;

FIG. 4 is a top view thereof;

FIG. 5 is a bottom view thereof;

FIG. 6 is a rear view thereof; and;

FIG. 7 is a front view thereof indicating when a plant needs watering.

The broken line showing is for illustrative purposes only and forms no part of the claimed design.
